Primary Examiner — Jeffrey D Asch*Assistant Examiner* — Rebekah A Caruso(74) *Attorney, Agent, or Firm* — Banner & Witcoff, Ltd.(57) **CLAIM**

The ornamental design for a shoe upper, as shown and described.

DESCRIPTION

FIG. 1 is a front perspective view of a shoe upper showing my new design;

FIG. 2 is a side view thereof;

FIG. 3 is a rear perspective view thereof;

FIG. 4 is a rear view thereof; and,

FIG. 5 is an enlarged view of FIG. 4 with subject matter that forms no part of the claimed design omitted.

The broken lines immediately adjacent to the shaded area represent the bounds of the claimed design and form no part thereof. The 9 unshaded regions within the shaded area, including the 3 circular eyelets and the 6 stadium-shaped openings at the base of each lace loop, that are demarcated by broken lines, form no part of the claimed design. The broken lines showing the remainder of the shoe are for environmental purposes only and form no part of the claimed design.
